UNITED STATES PATENT OFFICE

151,155

DESIGN FOR A SUN-BATHING AWNING

Olaf D. Koski, Seattle, Wash.

Application October 4, 1946, Serial No. 133,767

Term of patent 14 years

(CL. D88—3)

To all whom it may concern:

Be it known that Olaf D. Koski, a citizen of the United States, residing at Seattle, county of King, Washington, has invented a new, original, and ornamental Design for a Sun-Bathing Awning, of which the following is a specification, reference being had to the accompanying drawing, forming a part thereof, in which

Figure 1 is a perspective view of a sun-bathing awning, showing my new design;

Figure 2 is a front elevational view of the sun-bathing awning shown in Figure 1; and

Figure 3 is a side elevational view of the sun-bathing awning shown in Figure 1.

I claim:

The ornamental design for a sun-bathing awning, as shown.

OLAF D. KOSKI.
